W. DAVIS

SAFETY PLUG

Filed July 26, 1926

FIG. 1

FIG. 2

WILLIAM DAVIS,
Inventor.

By: Ben V. Zillman
Attorney.

UNITED STATES PATENT OFFICE.

WILLIAM DAVIS, OF ST. LOUIS, MISSOURI, ASSIGNOR OF ONE-HALF TO ITALIAN-
SWISS COLONY, OF SAN FRANCISCO, CALIFORNIA, A CORPORATION OF CALIFORNIA.

SAFETY PLUG.

Application filed July 26, 1926. Serial No. 124,800.

My invention relates to improvements in safety plugs, and more particularly to plugs adapted to be inserted in receptacles or containers containing liquids, and wherein the pressures of gases within the receptacle is automatically kept within a certain predetermined limit, and as soon as this limit of pressure within the container is exceeded, said plug will act to relieve the pressure within 10 said container and permit it to drop.

Another object of my invention is to provide means in a plug of the kind described, whereby the passage of gas under pressure is permitted, but whereby the flow of liquid 15 through the plug is obstructed and retarded.

Another object of my invention is to provide means on a plug of the kind described, whereby the insertion of said plug into a container is limited, so that there is no danger of 20 accidentally or carelessly driving the plug too far into the opening of the container and thereby shut off the outlet end of the gas-relief passage therethrough.

This invention has among its other objects, 25 the production of a plug of the kind described, which shall be simple, safe and reliable in its action, sturdy in construction, and efficient and satisfactory for use wherever found applicable.

Many other objects and advantages of the 30 construction herein shown and described will be obvious to those skilled in the art to which this invention appertains, from the disclosures herein given.

To this end, my invention consists in the 35 novel construction, arrangement and combination of parts herein shown and described, and more particularly pointed out in the claims.

In the drawings, wherein like reference 40 characters indicate like or corresponding parts,

Figure 1 is a sectional view, showing the 45 plug in operative position in the opening of a container; and

Figure 2 is a vertical elevation of the plug.

In the drawings, wherein I have illustrated 50 the preferred embodiment of my invention, 3 indicates a receptacle or container of any desired size and shape, adapted particularly to contain liquids therein, the level of said liquid being indicated at 4. At some suitable point in the container, as through its top wall 5 there is placed an opening 6, into which it 55 is intended to insert my improved safety

plug to control the pressure within the container.

The plug comprises a body part, preferably tapered toward its lower end as at 7, so that the plug may be easily inserted within 60 the preferably tapered opening 6 of the container.

Intermediate the ends of the plug, the same is recessed to provide a groove or channel 8 adapted to receive an elastic band 9 for a 65 purpose to be more clearly hereinafter described.

One or more radial passages 10 lead inwardly from the periphery of the annular groove 8, and an axial or longitudinal passage 11, of somewhat larger bore than the 70 passages 10, lead upwardly from the lower end of the plug and communicate with the inner ends of the radial passages 10, as shown.

When the plug is inserted in the position 75 shown in the drawings, with the lower end of the plug at a distance above the top of the liquid level within the container, the pressure within said container will be automatically taken care of, and relief of said 80 pressure will be had whenever it exceeds a certain predetermined amount. The band 9, which may be the ordinary "rubber band" of the desired size, and thickness or strength, normally seals the passage of gas through the 85 passages 10 and 11, but as soon as the pressure within the container exceeds an amount sufficient to overcome the tension of the band, this gas will flow through the passages, moving or lifting the band and escape into the 90 atmosphere. It is obvious that as soon as the pressure drops to the normal amount, the band will contract or seat itself in the groove, again sealing the passage until the 95 pressure again exceeds the predetermined amount.

It is essential that the outlet ends of the 100 passages 10 be at a point where the gas may escape into the atmosphere, and therefore in order to insure that the plug will not be driven too far into the opening in the container, either intentionally or carelessly, I 105 have provided a shoulder 12 intermediate the lower end of the plug and the groove 8. When driving the plug securely into place, this shoulder will be driven against the top surface of the wall 5 of the container and thereby limit further movement of the plug.

An ordinary nail 13 may be driven through 110 the plug, as shown, in lieu of providing a

shoulder 12 thereon, or in addition thereto, if preferred, this nail also acting to limit the downward movement of the plug into the opening.

- 5 In order to obstruct the flow of liquid through the passages of the plug, while permitting the flow of gas under pressure therethrough, I have provided a small sack 14, containing a quantity of small shot or similar
- 10 suitable solid particles 15, therein, and insert this sack into the main axial passage 11 intermediate the ends of the latter. A screen 16 may be placed across the passage 11 above the shot, in order to limit the insertion of
- 15 the latter and to prevent any clogging of the small passages 10.

The bag 14 may be tied intermediate its ends as at 16 to retain the particles 15 in place and prevent their dropping into the liquid

- 20 within the container 3, the lower end of said bag being tightly compacted within the bore 11 as shown at 17.

From the foregoing description it will be seen that liquids can not be splashed or otherwise accidentally conducted through the passages 10 and 11, the container being shipped in the upright position shown and stored in the same position, the tightly compacted lower end of the bag, and the solid, massed particles 15 also obstructing any flow of liquid out of the passages. However, when the pressure within the container exceeds the amount controlled by the strength of the rubber band, it will exert sufficient force to push this band aside or lift the same and such excess gas will escape into the atmosphere, the band automatically contracting again as soon as the pressure of the gas subsides or is relieved.

Having thus described my invention, it is obvious that various immaterial modifications may be made in the same without de-

parting from the spirit of my invention; hence I do not wish to be understood as limiting myself to the exact form, construction, arrangement and combination of parts herein shown and described, or uses mentioned, except as limited by the claims.

What I claim as new and desire to secure by Letters Patent is:

1. A safety device comprising a plug 50 adapted to be inserted into the opening of a container and extend thereabove, said plug having an opening therethrough communicating at one end with the interior of said container and at its other end with the periphery of said plug at a point above said container, means in said opening of the plug to obstruct the flow of liquid therethrough, a screen intermediate said last-mentioned means and the exterior end of said opening 60 of the plug, and means exteriorly only of the exterior end of said passage and normally sealing said passage thereat to prevent flow of gas therethrough except when the pressure of said gas exceeds a predetermined amount. 65

2. A safety device comprising a plug adapted to be inserted into the opening of a receptacle and project thereabove, a radial passage leading inwardly from the periphery at said projecting end of the plug, a longitudinal opening leading from the inner end of said radial passage and opening at the lower end of said plug, an elastic band encircling said plug at said radial passage and normally sealing the outlet end of the same, and means for obstructing the flow of liquid through said passage, comprising a plurality of solid particles, means for retaining said particles within said passage and filling the lower end of the passage. 75

WILLIAM DAVIS.
